PREPARATION OF DL-MENTHONE

Arthur L. Barney, West Lafayette, Ind., assignor
to Purdue Research Foundation, La Fayette,
Ind., a corporation of Indiana

No Drawing. Application August 18, 1942,
Serial No. 455,219

2 Claims. (Cl. 260—587)

1

This invention is concerned with the preparation of dl-menthone and is particularly directed to a process for the isolation of dl-menthone by rectification from mixtures initially comprising substantial quantities of isomers and precursors thereof.

The synthesis of menthol from isopropyl methyl phenol has been accomplished by hydrogenation of thymol (2-isopropyl-5-methylphenol) subsequent separation of dl-menthone from the resultant mixed reaction product, and reduction of the menthone to form menthol. This process has been described and claimed in my co-pending application Serial 441,466 filed May 2, 1942, now abandoned, of which the present application is a continuation-in-part.

One disadvantage accruing to the above process is the relatively low yield of dl-menthone normally obtainable from the hydrogenation of thymol. The crude reaction product obtained by such hydrogenation is a complex mixture of ketonic and alcoholic products from which dl-menthone should be isolated in substantially pure form prior to subsequent reduction if a dl-menthol product of reasonable purity is to be obtained. While the foregoing process is operable as far as the preparation and separation of the dl-menthone formed during the hydrogenation is concerned, improved procedures whereby a higher percentage of dl-menthone may be formed and separated are to be desired.

It is an object of the present invention to provide a process for the recovery of dl-menthone in high yields from the hydrogenation products of thymol. It is a further object to provide means whereby ketonic and alcoholic products embodying hexahydro-isopropyl-methyl-phenyl structures may be so modified as to permit the recovery therefrom of dl-menthone in high yield. Another object of the invention is to provide a method whereby a higher over-all yield of dl-menthol can be obtained from dl-menthone. Other objects of the invention will become apparent from the following specification.

I have discovered that when alcoholic and ketonic mixtures comprising hexahydro-thymol and the corresponding ketones (similar to those obtained by the hydrogenation of thymol) are rectified in the presence of copper chromite, Raney nickel catalyst, with or without additional alkali metal base, a rearrangement or combined rearrangement and dehydrogenation takes place whereby all or essentially all of such alcoholic and ketonic products become transformed to dl-menthone and are recoverable as such.

2

As raw materials in this process, any mixed product of the reduction of thymol products such as hydrogenated piperitone regardless of method of preparation, may be employed. If preferred, any dl-menthone initially present in such mixture may be stripped off and the residues employed in the present process. A further raw material consists of essentially alcohol-free ketone mixtures rich in menthones, and isomenthones. 5 An additional source of raw material resides in the impure fore-fractions and residues from the distillation of synthetic dl-menthol as described in my co-pending application as above-identified. Likewise substantially pure isomenthone 10 may be employed. It is to be understood that the present invention is not limited in any way to the use of products obtained by the hydrogenation of thymol. While the latter constitutes a preferred embodiment of the invention, similar products, regardless of the manner in which they are prepared, may be substituted therefor.

In operating in accordance with my new process, a certain amount of discretion may be exercised in the choice of the catalyst employed. For the treatment of compositions consisting essentially of alcohols or of ketone-alcohol mixtures comprising an appreciable proportion of the alcoholic constituent, a mixture of the copper chromite catalyst and alkali metal base is preferably employed. Where the raw material to be treated consists essentially of ketones, the alkali metal base alone may be sufficient. In the event Raney nickel is employed, the small amount of alkali present therein permits of its use alone provided sufficient quantities thereof are employed. 25

The procedure may be carried out at any suitable temperature and with any suitable proportion of catalyst. The operable range appears to be at a pot temperature of between about the boiling temperature of dl-menthone at the pressure employed and the temperature at which decomposition of the reaction mixture takes place, and generally not to exceed about 200° C. The preferred temperature to a considerable degree determined by the nature of the alcohol, ketone, or alcohol-ketone mixture employed, the proportion of catalyst included in the mixture to be rectified, the reflux ratio of the rectification tower, and the efficiency of the tower. Similarly, the proportion 30 of catalyst required is a function of the foregoing elements plus the temperature of operation. From about 1 to about 10 per cent of the Raney nickel or copper chromite catalyst and/or from about 0.1 to 1 per cent or higher, of sodium hydroxide, all based upon the weight of the rectifi- 35

cation mixture, may be employed. The preferred reflux ratio at which rectification is carried out is similarly dependent upon the efficiency of the rectification column, the nature of the product under treatment, the nature and proportion of catalyst, and the temperature of operation.

In carrying out the reaction the catalyst and ketonic or alcoholic product are mixed together in the pot of the rectification apparatus and heated to the desired temperature under reduced pressure. The dl-menthone is recovered as a lower-boiling fraction from the rectification. Higher-boiling fractions or residues may be re-utilized in the process.

The following examples illustrate the invention but are not to be construed as limiting the same.

Example 1

One hundred thirty three milliliters of a mixed ketonic product consisting predominately of dl-isomenthone but containing small amounts of isomeric menthols, 0.1 gram of sodium hydroxide, and 2 grams of Raney nickel catalyst were mixed together and rectified in a 60 plate column under reduced pressure. A small portion of the reaction mixture was lost due to a small leak developing in the apparatus. The remainder of the charge was rectified at a high reflux ratio to obtain a substantially quantitative yield of pure dl-menthone boiling at 75°-77° C. at 20 millimeters pressure and forming a semicarbazone melting at 156°-158° C. A semicarbazone preparation of the original material melted at from 147° to 194° C. The residue from the distillation amounted to less than 5 grams.

Example 2

One hundred forty three grams of hexahydro-thymol, 10 grams of Raney nickel catalyst, and 0.5 gram of sodium hydroxide were mixed together and rectified under reduced pressure at a bath temperature of 140°-150° C. and under high reflux ratio through a 60-plate column. The recovery of dl-menthone amounted to substantially 100 per cent of theoretical. To obtain this result, it was found necessary to add small additional amounts of Raney nickel catalyst from time to time during the rectification operation. The residue from this operation consisted essentially of nickel and sodium hydroxide.

Example 3

One hundred ninety two milliliters of crude hydrogenated thymol (containing both alcoholic and ketonic products and 10-15 per cent of petroleum ether), and 10 grams of Raney nickel catalyst were mixed together and rectified under reduced pressure through a 60 plate column substantially as described in the preceding example. As a product from this rectification, there was obtained 25 milliliters of petroleum ether and 108 milliliters of dl-menthone. A higher boiling fraction consisted of 14 milliliters of a mixture of dl-menthone and thymol. The latter was apparently carried over unreacted in the crude hydrogenation product or was produced by dehydrogenation of menthone and/or isomenthone. The residue from the operation consisted of 5 grams of thymol and 10 grams of nickel.

Example 4

A mixture obtained from the chromic acid oxidation of hexahydro-thymol and comprising approximately 90 per cent ketonic products was

mixed with 1 per cent by weight of solid sodium hydroxide. This mixture was charged into a distillation pot and rectified under reduced pressure and high reflux ratio through a 9-foot glass tower packed with $\frac{1}{2}$ inch Raschig rings and having an efficiency of 15-20 plates. The product from this reaction corresponded closely in characteristic to pure dl-menthone.

Example 5

The procedure of Example 2 was repeated, 8 grams of copper chromite catalyst being substituted for the Raney nickel. The results obtained were substantially the same as those of Example 2, except that it was unnecessary to supply additional quantities of catalyst during the rectification operation.

As described in said co-pending application, dl-menthone may be reduced with finely divided sodium and an ether such as dibutyl ether or a heavy mineral oil; or with calcium and a dialkyl ether; or with hydrogen and nickel in methyl alcohol or other solvents; or, by other procedures. This procedure yields dl-neomenthol concurrently with dl-menthol. Such dl-neomenthol may be recycled in the process hereinbefore described and substantially converted to dl-menthone, whereby the yield of dl-menthol is substantially increased.

While the foregoing examples have been primarily concerned with the rectification of hydrogenation products of thymol, it is to be understood that equivalent materials, regardless of source, may be substituted therefore to produce the desired dl-menthone. Similarly, in place of sodium hydroxide, potassium hydroxide or other base may be employed. The catalyst employed in combination with the dehydrogenation catalyst may be defined as a substance capable of promoting the attainment of equilibrium in ketonol systems. Thus, the described procedure may be carried out with any alcohol or ketone product embodying hexahydro-isopropyl-methyl-phenyl radicals in which the oxygen atom and at least one of the alkyl groups are on adjacent carbon atoms in the presence of the dehydrogenation, isomerization, or dehydrogenation-isomerization catalysts as herein described.

I claim:

1. The method which includes: heating a material selected from the group consisting of menthols and menthones other than dl-menthone, at its boiling point under the pressure employed, with a catalyst selected from the group consisting of Raney nickel and copper chromite, and in the presence of an alkali metal base; and, condensing the dl-menthone vapors produced.

2. The process as claimed in claim 1, wherein the starting material treated is a mixture of menthol and menthone materials.

ARTHUR L. BARNEY.
